G. C. GREEN.

RAILROAD TIE

APPLICATION FILED MAY 7, 1910.

974,788.

Patented Nov. 8, 1910.

UNITED STATES PATENT OFFICE.

GRANT C. GREEN, OF BEAUMONT, TEXAS

RAILROAD-TIE.

974,788.

Specification of Letters Patent.

Patented Nov. 8, 1910.

Application filed May 7, 1910. Serial No. 559,981.

To all whom it may concern:

Be it known that I, GRANT C. GREEN, a citizen of the United States of America, residing at Beaumont, in the county of Jefferson and State of Texas, have invented certain new and useful Improvements in Railroad-Ties, of which the following is a specification, reference being had therein to the accompanying drawing.

10 My invention relates to improvements in railway ties, and has for its object to provide rail-supporting and securing means adapted to be mounted preferably on concrete ties by means of which the jarring and straining 15 incident to the passing of cars over the ties will be reduced to a minimum.

Other objects and advantages of my invention will appear in the course of the following specification.

20 In the accompanying drawings: Figure 1 is a longitudinal sectional view of a railway tie and rail-supporting and securing means constructed in accordance with my invention, the portions of the tie adjacent each end of the rail-supporting and securing 25 means being broken off. Fig. 2 is a top plan view of the same. Fig. 3 is a cross sectional view on the line 3—3, of Fig. 1, looking toward the side of the rail. Fig. 4 is a 30 view of that portion of the rail plate in which the rail channel is located.

Referring to the drawings, which illustrate the preferred embodiment of my invention, 1 designates the tie, which is constructed preferably of substantially equal quantities of cement and sharp sand, and has arranged longitudinally of and embedded in the tie during the process of molding a plurality of twisted steel rods 2. Only a 40 section of the tie adjacent one of the rail-supporting and securing means is shown as the other rail-supporting and securing means, at the other end of the tie, is a duplicate thereof, and, hence, an illustration and 45 description of one of them will suffice for both. The base or under face 3 of the tie is flat with the sides 4 rising perpendicularly from the base for a short distance and then inclined slightly toward each other, as at 5, 50 to a flat top 6.

In the top 6, and near each end thereof, are wide, shallow, transverse recesses or depressions 7, which extend across the top of the tie and are provided with parallel, vertical sides 8. Centrally of each recess 7 is a circular socket or aperture 9, which extends

well into the tie and at right angles to the top 6 thereof. Fitting in each recess 7 is an oblong rail plate 10, preferably of malleable cast iron, which extends above the top 6 of the tie, as illustrated. The rail plate 10 is secured in position in the recess by means of bolts 11, preferably four in number, two arranged near each end of the plate. The bolts pass through apertures 12 in the 65 rail plate, which apertures register with threaded apertures 13 formed in metal blocks 14. The blocks 14 are preferably molded in the tie with their upper faces flush with the surface of the bottom of the 70 recess 7. One side 14^a of each block is downwardly and outwardly inclined from the top to the bottom to give a firmer hold in the tie and prevent its withdrawal if for any reason the block should work loose. 75

Centrally of the rail plate 10 is a transverse depression or rail channel 15 having perpendicular, parallel sides. Centrally of the rail channel 15, which is made of sufficient width to accommodate the base of the 80 desired weight of rail, is a circular aperture 16, which is the width of the channel and is the same diameter as the socket 9 and registers with it. In the bottom of the socket 9 is a circular metal plate 17 on which 85 rests the bottom of a coil spring 18. The coil spring is of a diameter a little less than that of the socket 9, so that it can be readily positioned in and removed from the socket. The upper portion of the coil spring extends 90 up through the aperture 16 and abuts against the under side of the base 19 of a rail 20 positioned in the rail channel 15 and holds the base of the rail above the bottom of the channel, as shown in Fig. 1. The base of 95 the rail, at one side, is held in the rail channel by means of a lug or projection 21, provided with a beveled under side 21^a, which is integral with the rail plate 10 and overhangs the top of the rail base at one side of 100 the web 20^a of the rail. In the rail plate 10, opposite the lug 21 and on the other side of the rail channel 15, is a threaded aperture 22 and screwed therein is a bolt 23 provided with an eccentric head 24, the under 105 side 25 of which is beveled and is adapted to extend over the top of the base 19 of the rail at that side of the web 20^a to keep that side of the base of the rail in the rail channel. As shown, the spring 18 forces the rail up 110 until the top of the base 19 of the rail abuts against the beveled under side 21^a of the

projection 21, and the beveled under side 25 of the bolt 23.

When a train passes, the rails are forced down against the tension of the coil springs 5 18, and, hence, the jar and shock to the tie is minimized, and the great advantage of this is apparent, as it is well-known that the heavy jarring and straining to which composition ties, owing to their rigidity, are 10 subjected by traffic soon renders them unfit for further service. So also with my tie will the jar and shock to the rails and rolling stock be proportionately reduced.

What I claim is:—

15 1. A tie provided with a socket, a rail chair carried by said tie, said rail chair being provided with a transverse recess, said recess being provided with a centrally located aperture registering with said socket, 20 a lug overhanging said aperture and adapted to engage one side of a rail base, a spring seated in said socket and adapted to contact with the base of a rail, said rail chair being provided opposite said lug with a 25 threaded opening and a securing bolt mounted in said threaded opening to engage the other side of a rail base.

2. A tie provided with a socket, a rail chair carried by said tie, said chair being 30 provided with an opening registering with said socket, a spring mounted in said socket and projecting through said opening, means for retaining a rail within said chair said

35 rail resting upon said spring, a plurality of metallic blocks mounted in said tie and provided with threaded openings, said chair being provided with openings registering with said threaded openings and bolts passing through said openings and into said threaded openings to retain said channel in 40 place.

3. A cement tie provided at each end with a transverse seat, each of said seats being provided with a centrally located socket, a rail chair mounted in each seat, means for retaining said chair within said seat, said chair being provided with an aperture 45 registering with said socket and means for detachably retaining a rail within said chair.

4. A tie provided with a socket, a rail 50 channel carried by said tie, a rail adapted to be positioned in said rail channel, said rail channel being provided with an aperture, said aperture in the rail channel being adapted to register with said socket, and 55 a spring positioned in said socket and adapted to project through the aperture in said rail channel and to bear against the underside of said rail to normally hold it above the bottom of said rail channel.

In testimony whereof I hereunto affix my signature in presence of two witnesses.

GRANT C. GREEN.
